DESIGN FOR ELECTRIC SCISSORS OR THE LIKE

Joseph C. Clark, Merchantville, N. J., assignor
to Atlas Instrument Company, Haddonfield,
N. J., a corporation of New Jersey

Application August 25, 1945, Serial No. 121,634

Term of patent 14 years

(Cl. D22—5)

To all whom it may concern:

Be it known that I, Joseph C. Clark, a citizen
of the United States, residing at Merchantville,
county of Camden, State of New Jersey, have
invented a new, original, and ornamental Design
for an Electric Scissors or the like, of which the
following is a specification, reference being had
to the accompanying drawing, forming part
thereof.

Fig. 1 represents a side elevational view of an
electric scissors showing my new design;

Fig. 2 represents a plan; and

Fig. 3 represents a front elevation thereof.

I claim:

The ornamental design for electric scissors or
the like, as shown.

JOSEPH C. CLARK.
